UNITED STATES PATENT OFFICE.

CHARLES SCHENCK, CYRUS W. BASSETT, AND EMIL IBACH, OF BETHLEHEM, PENNSYLVANIA, ASSIGNORS TO BETHLEHEM STEEL COMPANY, OF BETHLEHEM, PENNSYLVANIA, A CORPORATION OF PENNSYLVANIA.

METAL WHEEL.

Application filed January 17, 1921, Serial No. 437,642. Renewed February 17, 1923.

To all whom it may concern:

Be it known that we, CHARLES SCHENCK and CYRUS W. BASSETT, citizens of the United States, and EMIL IBACH, a citizen 5 of the Republic of Germany, residing at Bethlehem, Northampton County, Pennsylvania, have jointly invented new and useful Improvements in Metal Wheels, of which the following is a specification, reference 10 being had to the accompanying drawings, in which—

Fig. 1 is an elevation of a wheel embodying our invention; Fig. 2 is a section on lines II—II of Fig. 1; and Fig. 3 is a section of 15 a modified form of our invention.

Our invention relates to metal wheels and comprises a wheel in which the rim, web, spokes and an annulus in the region of the hub are all cast in one piece. Our invention 20 also consists in the features which we shall hereinafter describe and claim.

Referring to the drawings, 2 indicates 25 the rim of the wheel, which in section is preferably of a gradually increasing thickness from the edges toward the center, where it joins a continuous web 3 arranged at right angles thereto. The spokes 4 are joined to the web 3 in the plane of the web, but as they extend toward the hub they are splayed 30 or staggered alternately so as to form two sets of spokes, one on either side the plane of the web. At their inner ends the spokes 4 merge into an annulus 5, which has a box like section, the inner face 6 of which forms 35 a bearing against the exterior of the hub 7. The vertical faces of the annulus 5 are engaged by a flange 8 on the hub and by a plate 9, which is apertured to slip over the hub barrel. The flange, plate and annulus are 40 secured firmly together by the bolts 10.

The spokes 4 are preferably formed with 45 ribs 11 thereon, which serve to give additional strength thereto.

We prefer to form the wheel, just de-

scribed, by casting, so that it may, with the 45 exception of the hub, be made in one piece. We have found that a wheel formed in the manner described is much lighter than the usual type of cast wheel, owing to the skeletonized form of the wheel and to the 50 comparatively thin sections of the spokes and the hollow section of the annulus. In Fig. 2 we have indicated core openings 12 through which core sand may be removed from the 55 annulus 5. These opening may, if desired, be closed in any suitable manner after the removal of the sand.

In Fig. 3 we have shown a modified form of our invention, in which the hub 7^a is cast integral with the annulus of the wheel. 60

The terms and expressions which we have employed are used as terms of description and not of limitation, and we have no intention, in the use of such terms and expressions, of excluding any mechanical equivalents 65 of the features shown and described, or portions thereof, but recognize that various structural modifications are possible within the scope of the invention claimed.

What we claim is:

1. In a metal wheel, a continuous rim, a web emerging from the inner face of the rim and at right angles thereto, spokes attached to the web in the plane of the web, but extending in the direction of the hub 75 out of the plane of the web, and an annulus in the region of the hub into the sides of which the spokes merge, the parts being cast integral.

2. A metal wheel, having a continuous 80 rim, a web attached thereto, a bearing for the hub, sets of spokes, each set extending from the web to a face of the hub bearing, the said parts being cast integral.

CHARLES SCHENCK.
CYRUS W. BASSETT.
EMIL IBACH.
